(57) **CLAIM**

The ornamental design for a hovering, strolling fishing rig as shown and described.

DESCRIPTION

FIG. 1 is an isometric view of a hovering, strolling fishing rig showing our new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top side plan view thereof; and,

FIG. 7 is a bottom side plan view thereof.

The broken lines depict portions that form no part of the claimed design.
